C. H. LEONARD

WRENCH

Filed Oct. 23, 1926

Inventor

Carl H. Leonard

By *Watson E. Coleman*

Attorney

UNITED STATES PATENT OFFICE.

CARL H. LEONARD, OF PENDER, NEBRASKA.

WRENCH.

Application filed October 23, 1926. Serial No. 143,736.

This invention relates to wrenches and it is an object of the invention to provide a tool of this kind which comprises a pair of relatively movable jaws normally in open or spaced arrangement together with handle operated means for causing said jaws to move one toward the other to properly engage the work and thereby dispensing with any supplemental or auxiliary adjusting means.

The invention consists in the details of construction and in the combination and arrangement of the several parts of my improved wrench whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a view in side elevation of a wrench constructed in accordance with an embodiment of my invention, a second position of certain of the parts being indicated by broken lines;

Figure 2 is a view in edge elevation of the structure as illustrated in Figure 1 with a portion broken away;

Figure 3 is a sectional view taken substantially on the line 3—3 of Figure 1.

As disclosed in the accompanying drawing, 1 denotes an elongated handle member having an intermediate arcuate portion 2 and continued at one end by a laterally extending arm 3. This arm 3 terminates in an outstanding jaw 4.

Slidably mounted on the arm 3 is a movable jaw 5 provided at opposite sides of the arm 3 with the pockets or openings 6 in which are freely engaged the spaced fingers 7 arranged at the outer end of the elongated arm 8.

Carried by the handle member 1 at opposite sides thereof and extending in the same general direction as the arm 3 are the plates 9 between which the second end portion of the arm 8 extends and pivotally supported thereby through the medium of the rivet 10 or the like. By this means, the arm 8 is adapted to have desired swinging movement to move the jaw 5 toward or from the jaw 4.

A second handle member 11 has one end

portion extending between the plates 9 and pivotally engaged therewith by a rivet 12 or the like. The pivoted portion of the handle member 11 is continued by the forked arm 14 substantially at right angles to the handle member 11 and which straddles the pivoted end portion of the arm 8.

The extremities of the forked arm 14 are pivotally connected by the rivet 15 or the like with a wedge block or member 16 snugly engaging between the arcuate portion 2 of the handle member 1 and the arm 8 so that when the handle member 11 is moved inwardly toward the adjacent end portion of the handle member 1, the forked arm 14 will swing outwardly in a direction toward the arm 3 causing the wedge member 16 to swing the arm 8 outwardly and moving the jaw 5 toward the jaw 4. This movement of the jaw 5 assures effective engagement with a nut or other work between the jaws 4 and 5, the wedge member 16 effectively locking the jaws in such engagement until the handle member 11 is released.

The arm 8 is constantly urged inwardly toward the handle member 1 by the spring leaf 17 having one end portion anchored, as at 18, to the pivoted end portion of the handle member 11, the opposite or free end portion of the spring leaf 17 being in direct contact with the arm 8.

The handle member 11 is constantly urged outwardly through the medium of the spring 19 interposed between the handle members 1 and 11 and, herein disclosed, as anchored, as at 20, to the handle member 1.

As is illustrated in Figure 1 of the drawing, the marginal portion of the arm 3 adjacent the outer end thereof is provided with a wire receiving notch 21 with which the body portion 5' of the jaw 5 is adapted to coact to provide an effective wire cutter.

The outer extremity of the handle member 1, as herein disclosed, is beveled, as at 22, to provide a screw-driver blade.

From the foregoing description it is thought to be obvious that a wrench constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself

to the precise arrangement and formation of the several parts herein shown in carrying out my invention in practice except as hereinafter claimed.

5 I claim:—

1. A wrench comprising a handle member provided with an arm, a jaw carried by said arm, a movable jaw slidable on the arm, a second arm carried by the handle member for swinging movement, an end portion of the second arm having sliding engagement with the movable jaw, a wedge member interposed between the second arm and the handle member and having movement independently of both the second arm and the handle member, and means for moving said wedge member in a direction to cause the second arm to slide the movable jaw toward the first jaw.
2. A wrench comprising a handle member provided with an arm, a jaw carried by said arm, a movable jaw slidable on the arm, a second arm carried by the handle member for swinging movement, an end portion of the second arm having sliding engagement with the movable jaw, a wedge member interposed between the second arm and the handle member and having movement independently of both the second arm and the handle member, means for moving said wedge member in a direction to cause the second arm to slide the movable jaw toward the first jaw, and means for constantly urging the second arm in the opposite direction.
3. A wrench comprising a handle member provided with an arm, a jaw carried by said arm, a movable jaw slidable on the arm, a second arm carried by the handle member for swinging movement, an end portion of the second arm having sliding engagement with the movable jaw, a wedge member interposed between the second arm and the handle member, and means for moving said wedge member in a direction to cause the second arm to slide the movable jaw toward the first jaw, said second arm carrying a fork freely engageable within pockets formed in the movable jaw.
4. A wrench comprising a handle member provided with an arm, a jaw carried by said arm, a movable jaw slidable on the arm, a second arm carried by the handle member for swinging movement, an end portion of

the second arm having sliding engagement with the movable jaw, a wedge member interposed between the second arm and the handle member and coacting therewith and having movement independently of both the second arm and the handle member, and means for moving said wedge member in a direction to cause the second arm to slide the movable jaw toward the first jaw, the portion of the handle member with which the wedge member coacts being substantially 55 arcuate.

5. A wrench comprising an elongated handle member including an arm, a jaw carried by said arm, a slidable jaw movable on the arm, outstanding plates carried by the handle member, a second arm pivotally held by the plates and having slidable contact with the movable jaw, a handle member pivotally supported by the plates, the pivoted end portion of the second handle member being continued by a fork straddling the second arm, a wedge member carried by the fork and interposed between the second arm and the first named handle member whereby movement of one of the handle members toward the other will cause the wedge member to move the second arm in a direction to slide the movable jaw toward the first named jaw.

6. A wrench comprising an elongated handle member including an arm, a jaw carried by said arm, a slidable jaw movable on the arm, outstanding plates carried by the handle member, a second arm pivotally held by the plates and having slidable contact with the movable jaw, a handle member pivotally supported by the plates, the pivoted end portion of the second handle member being continued by a fork straddling the second arm, a wedge member carried by the fork and interposed between the second arm and the first named handle member whereby movement of one of the handle members toward the other will cause the wedge member to move the second arm in a direction to slide the movable jaw toward the first named jaw, and means for normally maintaining the adjacent portions of the handle members separated.

In testimony whereof I hereunto affix my signature.

CARL H. LEONARD.
